UNITED STATES PATENT OFFICE

FRANK W. MILLER, OF CHICAGO, ILLINOIS

LOCOMOTIVE REFILLING APPARATUS

Application filed March 28, 1927. Serial No. 178,939.

This invention pertains in general to apparatus adapted for refilling locomotive boilers with water at high temperatures productive of steam at pressures equivalent to the operating pressures of locomotive boilers.

5 A problem of increasing importance which must be coped with, wherever locomotive terminals of any considerable size are located within or close to cities, is the necessity of smoke elimination. In addition to the foregoing problem which is a matter of interest to the inhabitants of such cities, there is another problem which pertains to railroad management, namely, the efficient handling of the locomotives in the terminals.

10 At intervals, the boilers of the locomotives must be blown off and washed out and thereafter each locomotive must be refilled again for use and operating steam pressures must be created in their boilers while the locomotives are still in the roundhouse or at least still in the yards adjacent to the roundhouse. Hitherto, after the washing operations, the boilers have been filled with warm water and 15 fired up with coal, this being the most common practice, the firing up causing the emission from the roundhouses of great clouds of smoke and noxious gases, against which public indignation has been aroused and city 20 ordinances and health laws directed. Such refilling and refiring has also been inefficient and wasteful. By means of this invention locomotives may be refilled and prepared for instant use without the creation of smoke 25 and noxious gases, and in addition to this new result, with an efficiency never before attained.

25 One of the objects of this invention is to provide means for efficiently refilling locomotive boilers at terminals with water productive of steam at locomotive boiler operating pressures in order that the locomotives may be ready for service.

30 Another object of this invention is to provide a means for refilling locomotive boilers and raising the steam pressure therein to operating pressure without the creation of any smoke or noxious gases.

35 Another object of this invention is to provide a system for accomplishing the two fore-

going objects utilizing the sources of water and steam which are already available at most locomotive terminals.

40 Another object of this invention is to provide a locomotive refilling system having means for keeping it constantly ready to give the refilling service necessary to put locomotives in condition for use, without creating any smoke nuisance.

45 Another object of the invention is to provide a refilling system capable of accomplishing some or all of the foregoing objects and which is particularly designed to operate at maximum efficiency under varying demands.

50 Still another object is to provide a locomotive refilling system adapted to maintain it self for instant service, the means and manner of keeping the system in such condition being not disturbed by uneven demands made 55 upon it.

55 Referring now to the drawing, the figure illustrates a preferred embodiment of this invention.

60 Illustrated diagrammatically therein is a locomotive 11 whose boiler contents may be blown off through the blow-off pipe 12 into a separator 13. The separator illustrated operates centrifugally to discharge water 65 through the pipe 14 into the washout tank 15. The steam discharged by the separator passes through the pipe 16 into a condenser 17.

65 A refill tank 18 is connected to the washout tank 15 by means of pipes 19—19 through 70 which water is pumped into the refill tank by means of the pump 21. The water thus received into the refill tank will have such 75 temperature as ordinarily exists in the washout tanks at the terminals. It is desirable that this water in the refill tank be raised to 80 as near boiling as possible, and this may be done by utilizing the blown-off steam from locomotives. A pump 22 forces a quantity of 85 the water from the refill tank through the pipe 23 into the condenser 17 where this hot water mixes with the steam being received 90 from the separator. The condenser here disclosed is provided with an automatic air vent 95 24. The condenser discharges into the refill 100

immediately to the top of the tank, the cooler water thus remaining in the bottom of the second tank so long as the incoming water from the pipe 31 is hotter than the water lying in the lower portions of the second tank. Consequently, the hottest water in the two tanks will be forced into the distributing main before any of the cooler water in the bottom of the second tank can rise toward the distributing main outlet. It is obvious therefore that before any newly supplied water at 200° could enter the distributing main, practically all of the water of higher temperature previously contained in the two storage tanks would be forced ahead of it into the distributing mains.

When the refilling system above described is used, a locomotive boiler after being washed out may be left empty until the time approaches when it is needed for service again. At the proper time, it may be connected to a refill drop and a small quantity of this superheated water will then be admitted to the boiler. As soon as the water enters the boiler, being released from its former high pressure, it will be converted into steam which will fill the boiler, and by regulating the amount of water admitted the boiler can be heated gradually to prevent uneven expansion of the metal yet to bring it up to a proper temperature for the admission of the final charge of superheated water. When the boiler has been conditioned, it will then be filled until the proper water level has been reached, there then being the requisite amount of water in the boiler, all thoroughly heated to a temperature which will maintain a steam pressure suitable for the operation of the locomotive. This conditioning and refilling of the boiler is thus accomplished without burning any fuel in the locomotive and creating any smoke. Furthermore, the entire operation is much more efficient than the previously used methods of boiler refilling. The locomotive, having been refilled with water, all of which is properly heated to maintain steam at locomotive boiler operating pressures, is then ready for service and may be maintained in that condition by the burning of a small amount of fuel in the fire box under conditions that will not produce smoke or by further connection with the boiler refilling system whereby the refilling system will constantly or frequently replenish the supply of superheated water.

While there are shown in the drawing two storage tanks connected in series, the system may be operated with one storage tank, or with more than two. Likewise, the number of heaters shown is capable of being varied. Other changes and modifications together with other objects and advantages not herein stated are inherent to and are comprehended within the scope of this invention.

Having shown and described the invention, I claim:

1. A locomotive boiler refilling system comprising a refill tank and means for conducting thereinto blown off water from locomotives, means for conducting the blow off steam from locomotives into said tank to raise the water temperature therein, a storage tank into which water from the refill tank is pumped, means for distributing water from said storage tank to points of use for refilling locomotives, a heater and means for supplying steam thereto approximately at locomotive boiler pressures, and means for recirculating the water in said storage tank and in said distributing means through said heater to maintain all of said water at temperatures productive of locomotive boiler pressures. 70
2. A locomotive boiler refilling system comprising a refill tank and means for conducting thereinto blown off water from locomotives, a condenser and means for conducting thereinto blown off steam from locomotives and hot water from the refill tank, means for conducting the condenser products into the refill tank to heat the water therein, a storage tank into which water from the refill tank is pumped, means for distributing water from said storage tank to points of use for refilling locomotives, a heater and means for supplying steam thereto approximately at locomotive boiler pressures, and means for recirculating the water in said storage tank and in said distributing means through said heater to maintain all of said water at temperatures productive of locomotive boiler pressures. 85
3. In a locomotive boiler refilling system a tank for storing water at locomotive boiler pressures, means for distributing said water from said tank to points of use for refilling locomotives, a heater, means for recirculating through the heater water drawn separately from the top and the bottom of said tank to heat to and maintain all the water in the high pressure portions of the system at substantially the same high temperatures, said temperatures being productive of steam at locomotive boiler pressures, and means for supplying water to the high pressure portions of the system whenever water is being discharged therefrom, the supply means, the recirculating means, the distributing means and the storage tank being so connected that most of the water in the tank having temperatures 90 higher than the newly supplied water will be discharged into the distributing means prior to any discharge thereto of any of the newly supplied water. 100
4. In a locomotive boiler refilling system, a plurality of tanks for storing water heated to temperatures productive of steam at locomotive boiler pressures, means for heating to and maintaining said water at said temperatures, and means for supplying water to one 110
5. In a locomotive boiler refilling system, a plurality of tanks for storing water heated to temperatures productive of steam at locomotive boiler pressures, means for heating to and maintaining said water at said temperatures, and means for supplying water to one 120
6. In a locomotive boiler refilling system, a plurality of tanks for storing water heated to temperatures productive of steam at locomotive boiler pressures, means for heating to and maintaining said water at said temperatures, and means for supplying water to one 130

of the tanks to be heated, and means for distributing water already heated to said temperature to points of discharge from the system, said supplying and distributing means communicating with the lower and upper portions respectively of said tanks to exhaust from each tank all of the water in such tanks having the same temperature before water of lower temperatures is taken from any one tank.

5. In a locomotive boiler refilling system, a storage tank for holding water at locomotive boiler temperatures and pressures, a heater, a refill drop means for distributing the hottest water from said tank to said refill drop, and means for recirculating variable proportions of water from the distributing means and from the bottom of said tanks through said heater to heat said water to and maintain it at the desired locomotive boiler temperatures.

6. A locomotive boiler refilling system comprising a blow-off line, a separator for separating the blown off steam and water, a blow-off tank to receive the blown off water, a refill tank, means for pumping the water from said blow-off tank into said refill tank, a blow-off steam line connecting said separator and said refill tank, a condenser interposed in said blow-off steam line, means for circulating water from said refill tank through said condenser, a storage tank, a heater, a refill line, means for delivering water from said refill tank under pressure into said storage tank, and means for maintaining a circulation of said water through said storage tank, refill line and heater.

7. In a locomotive boiler refilling system, a storage tank whose capacity equals that of a plurality of locomotive boilers, a distributing main connected therewith, a pump connected for delivering water into said tank and main and for maintaining a predetermined pressure on the water in the tank and main, a water heater having a capacity small relatively to the storage capacity of said tank and main, a second pump for positively and continuously circulating water from said tank and main through said heater without reduction in pressure thereof, and means for supplying steam to said heater to raise the water temperatures therein well above 212° F.

8. In a locomotive boiler refilling system, a storage tank having a capacity equal to that of a plurality of locomotives and a refilling main connected therewith, a pump connected for delivering water into said tank and main and arranged for continuously maintaining pressure on the water in said tank and main, a heater separate from the storage tank and having a relatively much smaller water storage capacity than said tank and connected with said tank and main, a pump connected for continuously recirculating water through

said heater and through the tank and main without reduction in pressure thereof, and means for supplying steam to said heater for raising the water therein well above 212° F.

In witness of the foregoing I affix my sig. 70
nature.
